UNITED STATES PATENT OFFICE

ALLEN P. WAGNER, OF JONESTOWN, PENNSYLVANIA

TABLE

Application filed May 5, 1927. Serial No. 189,072.

This invention relates to cabinets and particularly to a cabinet having a folded table therein.

In the present day constructions of apartments and small houses, there has come to be a demand for furniture which can be easily gotten out of the way to leave space in the room while at the same time giving maximum efficiency when in use. There is a demand for 10 a folding table in both dining rooms and kitchens. In order to be successful, this table must be easily folded and unfolded, should be simple, with few parts and yet solid when being used.

15 The primary object of this invention is the provision of such a combined cabinet and table as will fill the above mentioned needs.

Another object of this invention is the provision of a cabinet-table which (1) will, when 20 folded, have no tendency to open, (2) when open, will have no tendency to close, regardless of the load and the position of the load, (3) can be opened to locked position by merely swinging the closure member of the 25 cabinet outwardly (4) can be closed by merely moving the closure member toward closed position, (5) has its inner end supported in a guide when in open position by upright members which lock the inner end of the 30 table in its highest position, (6) will have the outer end of a main table section hinged to the upper edge of a door section and (7) will have a folding extension for the main table section and means for supporting the same 35 in extended position.

Referring to the drawings wherein I have illustrated an embodiment of my invention.

Fig. 1 is a front view of my combined cabinet and table, the table being folded and 40 the cabinet closed.

Fig. 2 is a view similar to Fig. 1 but showing the cabinet open and the table extended.

Fig. 3 is a side view of my invention showing the side broken away to disclose the position of the parts when the cabinet is closed.

Fig. 4 is a view similar to Fig. 3 but with the table in a half open position.

Fig. 5 is a view showing the table open and 50 unfolded to full length.

Fig. 6 is a fragmental sectional view on the line 6—6 of Fig. 1.

Fig. 7 is a fragmental sectional view on the line 7—7 of Fig. 5.

Fig. 8 is a sectional view on the line 8—8 55 of Fig. 2.

In the drawing, the same reference characters refer to the same or similar parts throughout the view.

The numeral 20 designates the front of the 60 cabinet of my invention, and 21, 22, the sides thereof.

At the top of the cabinet I have provided two doors 23, 24. Behind these doors I have provided shelves 25 and a swinging drawer 65 26. These shelves per se are not a part of my invention and will not be further described.

The lower portion of the cabinet is provided with my improved cabinet table, the 70 main table top member being designated by the numeral 27. At the outer edge of the main table top member 27 is a folding table top section 28 shown folded in Figs. 3 and 4 and extended or unfolded in Figs. 1 and 5. 75 Adjacent the underside of the main table top member 27 are guides 29, each having a groove 30. Coacting with the grooves 30 are tongues 31 of the frame member 32. Extending forwardly from the frame member 32 are 80 sliding support members 33. These support members 33 extend outwardly from the frame member 32 and pass through openings in the cross piece 34 which latter serves to reinforce the main table top member 27. 85

Midway between the support members 33 is a pull-rod 35 having a handle 36 on its end. This pull-rod 35 extends through the cross piece 34 as shown in Fig. 6, the handle 36 being shown also on Fig. 2. It will thus be 90 seen that when the handle 36 is pulled outwardly, the support members 33 will be forced outwardly to a position where, when the folding table top extension 28 is extended, it will rest on the upper surfaces of these support members. 95

The rear of the main table top member 27 is provided with lugs at each side which I have designated at 37. These lugs extend into and are guided by guideways 38. These 100

guideways may be of any suitable construction as of metal and are secured to the insides of the walls 21, 22 of the cabinet. They are placed preferably in a vertical position, as the table is brought out to operative position, the lugs 37 move to the top of the guideways 38 and when the table is replaced in the cabinet, the lugs move toward the bottom of the guideways 38.

10 The support for the table comprises essentially two parts, the lower part being pivoted to the support as the front 20 of the cabinet and the upper part being pivoted to the table top section adjacent its outer end and the upper part at its lower end being pivoted adjacent the middle of the lower part.

This upper part of the support has been utilized as a door in the embodiment shown and has been designated by the numeral 39. 20 The lower part of the support is also shown in the present embodiment as a panel member 40. This panel member comprises two uprights 41 which are attached to its inner side and extend upwardly to a point where 25 when the table is extended to a horizontal position, their upper ends will engage the bottom of the main table top section 27. When in this position, the uprights 41 will securely hold the table top section 27 in position regardless of the weight on the table. No matter how the table load is distributed, the forward end of the table is held up by the support member 39, the lower end of which is held in position by the lower support member 40. The lower support member 40 being held in place by the support member 39, the upper ends of the uprights 41 prevent the movement of the inner end of the table in a downward direction, the guides 37 preventing movement in any other direction.

When it is desired to move the table from closed position as illustrated in Figs. 1 and 3, it is only necessary to release the catch 42 and pull outwardly. This action causes the 45 table top section 27 to leave its vertical position shown in Fig. 3 and approach the position shown in Fig. 4. As soon as this movement begins, the lugs or pins 37 move upwardly in the guideways 38. The outward movement of the table top section 27 moves the uprights 41 and the support 40 outwardly about its pivot as shown in Fig. 4. When a certain point is reached as the table 50 top section 27 approaches the horizontal, the support 40 and the uprights 41 move inwardly under the influence of the pressure from the support 40 due to the weight of the table top section 27. As the latter reaches the horizontal, the uprights 41 return to vertical 55 position and the folding top member 28 is ready to unfold. The handle 36 is now pulled outwardly. This brings the supports 38 outwardly as has already been described. The folding top member 28 is now swung to 60 its operative position.

In closing the table within the cabinet, the reverse operations are followed, the folding top member being folded, the handle 36 being pushed in and the support panel 39 being raised. As soon as the upward movement of the panel support 39 begins, a pull is exerted 70 on the support member 40. This swings the uprights 41 outwardly and permits the rear of the table to fall, the same being guided by the guideway 38. The parts then return to folded closed positions as indicated in Fig. 3.

It is thus clear that with a minimum number of parts I have provided a folding table construction wherein there is no tendency to close under the influence of the load on the table and it will also be observed that with the catch 42 loosened, the weight of the table etc. will be all inwardly of the hinges of the supports 39, 40 and consequently there will be no tendency to open until force is applied. At the same time as part of the parts are coming down while others are going up, during the opening movement, very little energy is required to bring about the movement.

While I have illustrated and described in detail an embodiment of my invention, it is to be understood that this showing and description is merely illustrative and that modifications and changes may be made without departing from the spirit of my invention and within the scope of the appended claims.

Having described my invention, what I claim and desire to secure by Letters Patent is:—

1. In combination, a support, a guide, a table having one end guided by said guide, a member pivoted to the support, a second member pivoted to the table and to the first member, the first member extending to a position to lock the guided end of the table in position when the table is extended.

2. In combination, a support, guides on the support, a table having a rear edge guided by the guides, a member pivoted to the support, a second member pivoted to the table and to the first member, the first member extending to a position to lock the guided end of the table in position when the table is extended.

3. In combination, a cabinet forming a support, guides mounted on the sides of the cabinet, a table having a rear edge guided by the guides, a member pivoted to the support, a second member pivoted to the table and to the first member, the first member extending to a position to lock the guided end of the table in position when the table is extended.

4. In combination, a support, guides on the support, a table having a rear edge guided by the guides, an upright member pivoted to the support, a second member pivoted to the first member, at a point adjacent the middle of the first member and having its opposite end pivoted to the table, the proportions of the table and the two members and guides being

such that the upper ends of the first member will lock the inner end of the table in the upper ends of the guides when the table is in a horizontal position.

5. In combination, a cabinet having a front door portion pivoted on a horizontal axis, a table pivoted to the door, means positively operated by the movement of the front door to its open position to a point beneath and in contact with the inner edge of the table to securely support the same in place.

6. In combination, a cabinet having a front door portion pivoted on a horizontal axis, a table pivoted to the door, swinging means positively operated by the movement of the front door to its open position to support the inner edge of the table securely in place the swinging means being upright when in its supporting position.

20 7. In combination, a cabinet having a front door portion pivoted on a horizontal axis, a table pivoted to the door, a member pivoted to the cabinet and to which the door is pivoted on its horizontal axis, the member being provided with an upstanding portion in position to have its end against the bottom of the table, to support the same when the table is in horizontal position.

8. In combination, a cabinet having two door portions, one of the door portions being pivoted at its lower edge to the cabinet, the other door portion being pivoted to the upper edge of the first door portion, guides on the cabinet wall a table having one edge pivoted to the second door portion and connections adjacent its opposite edge and coacting with the guides, extensions extending upwardly from the lower door portion and extending upwardly to a point where they will engage the bottom of the table when the latter is in horizontal position.

9. In combination, a cabinet having two door portions, one of the door portions being pivoted at its lower edge to the cabinet, the other door portion being pivoted to the upper edge of the first door portion, guides on the cabinet wall, a table top member having one edge pivoted adjacent the top of the second door portion and connections coacting with the guides, extensions extending upwardly from the lower door portion, and extending upwardly to a point where they will engage the bottom of the table when the latter is in horizontal position and a folding table top section pivoted adjacent the outer edge of the table top member.

10. In combination, a cabinet having two door portions, one of the door portions being pivoted at its lower edge to the cabinet, the other door portion being pivoted to the upper edge of the first door portion, guides on the cabinet wall, a table top member having one edge pivoted adjacent the top of the second door portion and connections coacting with the guides, extensions extending upwardly

from the lower door portion, and extending upwardly to a point where they will engage the bottom of the table when the latter is in horizontal position, a folding table top section pivoted adjacent the outer edge of the table top member and means for supporting the folding table top section when it is unfolded, including means slidable beneath the surface of the table top member.

11. In furniture of the character described, the combination with a casing having a pocket formed therein, of a panel, means connecting the lower end of the panel and the bottom portion of the pocket for permitting said panel to swing against said casing over said pocket, a table leaf hinged to the upper end of the panel and foldable to lie along the inner surface of the panel, a second table leaf of substantially the same dimensions as the first-named leaf and hinged to the outer end of the first-named table leaf to permit the leaves to be folded one on top of the other in alignment or extended with relation to each other, and means carried by the first-named leaf and adapted to be extended from the end thereof to form a support for the second named leaf when unfolded.

In testimony whereof I hereunto affix my signature.
